UNITED STATES PATENT OFFICE.

FRANK M. MORTON, OF PHOENIX, ALABAMA, ASSIGNOR TO THE COLUMBUS TRUCK
AND SUPPLY MANUFACTURING COMPANY, OF COLUMBUS, GEORGIA, A CORPORA-
TION OF GEORGIA.

REEL.

1,116,608.

Specification of Letters Patent.

Patented Nov. 10, 1914.

Original application filed April 4, 1912, Serial No. 688,420. Divided and this application filed March 27,
1913. Serial No. 757,219.

To all whom it may concern:

Be it known that I, FRANK M. MORTON, a citizen of the United States, residing at Phoenix city, in the county of Lee and State 5 of Alabama, have invented certain new and useful Improvements in Reels; and I do declare the following to be a full, clear, and exact description of the invention, such as will enable others skilled in the art to which 10 it appertains to make and use the same.

This invention relates to winding and reeling, and more especially to reels such as the warper beams used in bleaching and dyeing, and whereon some flexible article such as 15 yarn is to be wound, although I do not wish to be limited to this use of the invention.

The present application is a division of my application on which Patent #1,062,493 issued to me on May 20, 1913.

20 The object of the latter is to provide improved means for distending the slats of a contractile or collapsible reel and for indicating from the exterior of the reel the position of the hidden distending mechanism and 25 hence the position of the slats themselves. This object is carried out in a manner hereinafter more fully described and claimed and as shown in the drawings wherein;—

Figure 1 is a central vertical longitudinal 30 section, showing my invention as used in connection with a warper beam; Figs. 2 and 3 are cross sections on the lines 2—2 and 3—3 respectively of Fig. 1; and, Fig. 4 is a side elevation of one of the expanders.

35 The reel in the present case comprises a main shaft 1 reduced at its ends to form shoulders 2, and a short distance beyond the shoulders said ends are threaded as at 3, beyond which they are still further reduced 40 to form journals 4 by means of which the reel is revolvably supported in bearings not necessary to illustrate. Mounted on the reduced portions against said shoulders 2 are heads 5 and 7 held respectively in place by 45 nuts 6 and 8 engaging the threads 3. This means of mounting the heads is given simply for purposes of illustration. The inner faces of the heads in the present instance are shown as provided with radial recesses or 50 grooves 10 forming guides for the slats hereinafter described, but otherwise the detailed construction, size, and material of these heads is unimportant. In the present instance also I have shown the heads as con-

nected by tie rods 12, although this detail is 55 entirely optional. One of the heads in the present case is shown as provided with radial ribs 15 for strengthening purposes, and on its outer side with an annular flange 16. Disposed between said heads are longitudinal slats 22 whose ends loosely engage said 60 radial guides 10 so that the slats may be distended by a mechanism yet to be described or may contract or recede toward the axis of the reel by virtue of the tension of the 65 yarn or other article wound thereon, and for this purpose the length of said guides is greater than the width of the slats radially of said reel. It is quite possible to provide other means on the heads for guiding the 70 slats in their movements outward and inward, but the recesses or grooves 10 are shown and described simply for purposes of illustration. The means for distending or expanding these slats constitutes the gist of 75 the present invention.

Slidably mounted on the shaft are the hubs 18 of expanding rings 17, the hubs and rims 20 preferably connected by spokes 19 as shown in Fig. 4, and each rim is by preference provided with radial notches 21 adapted to co-act with beveled expanding blocks 26 on the inner edges of the various slats. Through eyes in the spokes of the various rings pass connecting rods 23 which 85 are suitably secured therein as by nuts 24, and by this means the rings are held rigidly spaced whether they are at rest or being moved. It is obvious that when the lower faces of the blocks 26 rest in the notches 21, 90 the slats will be contracted toward the axial shaft by the tension of the yarn or other article wound on the reel; and on the contrary when the rings are adjusted longitudinally on the shaft 1 so that the notches travel to 95 or toward the high ends of the blocks 26, the various slats are distended radially of the reel as the loose engagement of their ends with the guides 10 will permit. The means for moving said rings longitudinally and 100 distending or permitting the contraction of said slats includes a screw 27 whose threads engage a threaded hole 28 in one of the spokes 19 of the endmost ring, and whose shank is revolvably mounted through a hole 105 in the reel-head 7 and has a fixed flange 29 at one side of the head and a collar 30 held on its shank by a set screw 30' and standing

at the other side of the head; while the outer head of this screw is squared as at 31 to receive a wrench or handle. When the latter is applied and the screw turned in the proper direction. The gang of rings 17 will be moved one way or the other with the results above set forth. In order to limit the degree to which said gang may be moved in either direction, I preferably provide a gage screw 32 whose threaded inner end engages a threaded hole 33 through one of the spokes of the endmost ring, preferably opposite to that carrying the hole 28; and this screw projects loosely through a hole in the head 7 and has a fixed flange 34 on its shank outside said head and a collar 35 adjustably mounted on its shank inside the head by means of a set screw 36. It is obvious that by loosening this set screw and adjusting the collar 35, the distance between it and the flange 34 can be increased or diminished so as to increase or reduce the path through which the gang or rings may move, and it is obvious moreover that by adjusting the position of this screw within the threaded hole 33, the entire gang of rings may be adjusted toward one head or the other within the reel, for which purpose I make the outer end of the screw square as shown at 37. Therefore this screw having its flange and collar spaced a greater distance than the thickness of the head 7, serves as a stop to limit the throw of the adjuster as well as the path through which said adjuster works, and its outer end also serves as means for indicating the position of the gang of rings and therefore the position of the adjuster. The other screw by being swiveled through the head 7 and rotated from the exterior, will of course serve as a means for moving the distending mechanism and expanding or permitting the contraction of the slats. I have shown the two screws as projecting through the same head, which will doubtless be the preferred construction, and I have omitted the provision of similar screws at the other end of the reel because I do not consider them necessary.

What is claimed as new is:

1. In a reel of the class described, the combination with heads having solid outer portions and one of which has an opening, and a series of collapsible slats arranged between them and adapted to be covered by the material upon the reel; of means for distending the slats, and indicating means connected with said distending means and operated by the same, said indicating means extending through said opening in one of the reel heads and movable longitudinally of the reel to indicate the position of the slats.

2. In a reel of the class described, the combination with heads having solid outer portions and one of which has an opening,

a series of collapsible slats arranged between them and adapted to be covered by the material upon the reel; of means for distending the slats, and an indicating screw adjustably engaged with said distending means and slidable through the opening in one of the heads and in a direction longitudinally of the reel to indicate the position of the slats. 70

3. In a reel of the class described, the combination with the heads, and a series of collapsible slats between them; of means movable longitudinally within the reel for distending the slats radially, actuating devices for the distending means rotatably mounted through one head, and means projecting slidably through one head for indicating the position of the slats. 75

4. In a reel of the class described, the combination with the heads, and a series of collapsible slats between them; of means movable longitudinally within the reel for distending the slats radially, actuating devices for the distending means rotatably mounted through one head, a member connected with said distending mechanism and moving slidably through one head, a flange on said member outside the head, and a collar adjustably mounted on this member inside the head, for the purpose set forth. 90

5. In a reel of the class described, the combination with the heads, and a series of collapsible slats between them; of means movable longitudinally within the reel for distending the slats radially, actuating devices for the distending means rotatably mounted through one head, a screw adjustably engaging said distending mechanism with its shank projecting through one head, a flange fixed on the shank of the screw and a collar adjustable thereon at opposite side of said head, for the purpose set forth. 100

6. In a reel of the class described, the combination with the heads, and a series of collapsible slats between them; of means movable longitudinally within the reel for distending the slats radially; a screw whose threads engage said distending mechanism and whose shank extends slidably through one head and has its outer end squared, and a second screw engaging said mechanism and having its shank passing loosely through the same head and carrying a fixed flange outside the same and an adjustable collar inside the same. 115

7. In a reel of the class described, the combination with the heads, and a series of collapsible slats between them; of means movable longitudinally within the reel for distending the slats radially, a screw whose threads engage said distending mechanism and whose shank passes loosely through one head and carries a fixed flange outside the same, a collar movably mounted on said shank inside of the head, a second screw 125

whose threads engage said mechanism and whose shank passes slidably through the hole in the same head, and stop devices on its shank outside and inside the head.

5 8. In a reel of the class described, the combination with a pair of heads, and movable slats between them; of longitudinally movable mechanism for distending the slats radially, a gage member carried by the actuating mechanism and passing loosely through one head, and stops on said member on opposite sides of the head, one stop member being adjustable longitudinally thereon.

15 9. In a reel of the class described, the combination with a pair of heads, a shaft connecting them, and movable slats between the heads; of a series of spaced rings slidably mounted on the shaft, beveled blocks on the slats with which said rings engage, means 20 for shifting said rings longitudinally of the shaft in unison and adjustable means for limiting the shifting movement of the rings.

25 10. In a reel of the class described, the combination with a pair of heads, a shaft connecting them, and movable slats between the heads; of a series of spaced rings slidably mounted on the shaft, beveled blocks on the slats with which said rings engage, rods connecting said rings so as to cause 30 them to move in unison, adjusting mechanism passing through one head and engaging the endmost ring and adjustable means for limiting the shifting movement of the rings.

35 11. In a reel of the class described, the combination with a pair of heads, a shaft connecting them, and movable slats between the heads; of a series of spaced rings slidably mounted on the shaft, beveled blocks 40 on the slats with which said rings engage, rods connecting said rings so as to cause them to move in unison, a screw swiveled through one head and having its threads engaging the endmost ring, and a member projecting from this ring through the same head to the exterior thereof, for the purpose 45 set forth.

12. In a reel of the class described, the combination with a shaft, heads carried 50 thereby, collapsible slats between said heads,

and a series of beveled blocks on each slat; of a series of rings slidably mounted on the shaft and having peripheral notches to receive said blocks, rods rigidly connecting said rings, means for moving the group of 55 rings and adjustable means for limiting the movement of said rings.

13. In a reel of the class described, the combination with a shaft, heads carried thereby, collapsible slats between said 60 heads, and a series of beveled blocks on each slat; of a series of rings slidably mounted on the shaft and having peripheral notches to receive said blocks, rods rigidly connecting said rings, means for moving the group 65 of rings, and an adjustable stop screw to limit the action of said last-named means.

14. In a reel of the class described, the combination with a shaft, heads carried thereby and having radial grooves, and collapsible slats whose ends are mounted loosely in said grooves; of beveled elements on the inner faces of said slats, a series of rings connected with each other and mounted slidably on said shaft and engaging said elements, adjustable means for limiting the movement of said rings and means on the exterior of the reel for adjusting the position of said rings, for the purpose set forth. 75

15. In a reel of the class described, the combination with a shaft, heads carried thereby and having radial guides, and collapsible slats whose ends are mounted loosely in said guides; of beveled blocks on the inner faces of said slats, a group of rings connected with each other and slidably mounted on said shaft and having notches in their peripheries engaging said blocks, means on the exterior of the reel for adjusting the position of said group longitudinally, and a 80 gage member projecting from said group through one head of the reel for indicating the position of the group and of the slats. 85

In testimony whereof I have hereunto set my hand in presence of two subscribing witnesses. 95
